(57) **CLAIM**

The ornamental design for a threaded connection pipe as shown and described.

DESCRIPTION

FIG. 1 is a perspective view of a threaded connection pipe showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is a bottom plan view thereof.

FIG. 9 an enlarged view of area 9 shown in FIG. 1; and,

FIG. 10 a sectional view of area 10 shown in FIG. 7.

The evenly spaced broken lines depict portions of the threaded connection pipe that form no part of the claimed design. The dot dash dot broken lines denote the boundaries of the detail areas and form no part of the claim.
